United States Patent Office

Des. 215,320
Patented Sept. 23, 1969

215,320

DECORATIVE FLORAL STAKE

Saul Klayman, Mattapan, Mass., assignor to Kandy-Pak, Inc, Roslindale, Mass.

Filed Aug. 23, 1968, Ser. No. 13,252

Term of patent 14 years

Int. Cl. D31

U.S. Cl. D35—1

FIG. 1

FIG. 1 is a perspective view of a decorative floral stake embodying my new design;

FIG. 2 is a perspective view of the lower section thereof;

FIG. 3 is an exploded perspective view of the upper and lower sections; and

FIG. 4 is an enlarged view of the lower section.

FIGURES 2, 3 and 4 are shown broken away for convenience of illustration.

The broken line representation of the potted plant in FIG. 1 is for purposes of illustration only.

I claim:

The ornamental design for a decorative floral stake, substantially as shown and described.
